UNITED STATES PATENT OFFICE.

ORTUS E. MOATS, OF CHICAGO, ILLINOIS, ASSIGNOR TO WESTERN WHEELED SCRAPER COMPANY, OF AURORA, ILLINOIS, A CORPORATION OF ILLINOIS.

ROAD PLANING AND FINISHING MACHINE.

1,335,906.

Specification of Letters Patent.

Patented Apr. 6, 1920.

Application filed August 18, 1915. Serial No. 46,122.

To all whom it may concern:

Be it known that I, ORTUS E. MOATS, a citizen of the United States, and a resident of Chicago, in the county of Cook and State 5 of Illinois, have invented certain new and useful Improvements in Road Planing and Finishing Machines, of which the following is a specification.

My invention relates to road making machines, and has for its object to provide a new and improved machine which will be well adapted to smooth, crown and roll a road so as to leave it in a finished condition. To this end, it contemplates a machine provided with extensible scrapers which project laterally from both sides of the machine frame and are adjustable to any desired angle, and also to be folded or withdrawn under the frame of the machine so that the 10 machine may readily be moved from place to place. It also contemplates the provision of a scarifier coöperating with such scrapers to break up or loosen the hard center of the road and enable the scrapers to properly 15 level and smooth it. It further contemplates the provision of a roller adapted to roll the road after the scrapers have passed over it and at the same time give it the proper crown. In connection with these generic 20 features my invention also includes mechanism by which the various adjustments of the scrapers, scarifier and roller may be efficiently accomplished, all of which is hereinafter described.

35 In the accompanying drawings,—

Figure 1 is a side elevation of my improved machine;

Fig. 2 is an enlarged detail, being a partial vertical cross-section on line 2—2 of 40 Fig. 4;

Fig. 3 is a plan view of the machine;

Fig. 4 is a plan view illustrating the operating parts of the machine which are carried under the main frame—to-wit, the 45 scrapers, the scarifier, and parts of the mechanism by which the scrapers are adjusted and held in operating position;

Fig. 5 is an enlarged detail, being a cross-section on line 5—5 of Fig. 4;

50 Fig. 6 is a cross-section on line 6—6 of Fig. 4;

Fig. 7 is a rear view illustrating the crowning roller, parts of the main frame and roller supporting frame being in section;

Fig. 8 is an end view of the crowning roller, showing the frame in which it is mounted and the mechanism for operating it;

Fig. 9 is a view, partly in section, illustrating the mounting of one of the cranes by which the lateral scrapers are manipulated;

Fig. 10 is a horizontal section on line 10—10 of Fig. 9;

Fig. 11 is a vertical section of one of the cranes on line 11—11 of Fig. 9; and

Fig. 12 is an enlarged detail, being a partial vertical section on line 12—12 of Fig. 3.

In the embodiment of my invention illustrated in the drawings: 13 indicates the main frame of the machine, which is preferably made up of I-beam material shaped substantially as outlined in Fig. 3,—that is to say, the rear portion of the frame is preferably rectangular, as is also the front end portion thereof, the latter being, however, considerably narrower than the rear end of the machine. The intermediate portion of the main frame tapers toward the front, as illustrated. It will be understood, of course, that the shape of the frame may be varied as convenience may suggest. The rear portion of the main frame is supported upon wheels 14 mounted on spindles carried by 50 an axle 15, which, as best shown in Fig. 7, extends over the main frame and is fixedly secured thereto in any suitable way. The front portion of the frame is supported by wheels 16 mounted on an axle 17, which as 55 best shown in Fig. 1, carries a lower fifth wheel member 18. A tongue 19 is connected with the lower fifth wheel member by means of tongue-irons 20, in the usual way, so that the machine may be steered by swinging the 60 tongue and thereby swinging the front axle. The front end of the main frame 13 is mounted on a bolster 21, which connects with the upper member 22 of the fifth wheel, the two members of the fifth wheel being 65 pivotally connected together by a king-bolt 23 passing through bars 24—25 connected, respectively, with the lower and upper members of the fifth wheel. 26—27 indicate supplemental bolsters between the forward 70 portion of the main frame and the upper member 22 of the fifth wheel; and 28 indicates a draft-bar secured between the rear end of the bolster 27 and the upper member 22 of the fifth wheel, the king-bolt 23 ex- 75

90

95

100

105

110

tending through the forward end of said draft-bar. 29 indicates an arched bar which is secured on the forward end of the main frame, its end portions extending downward 5 and outward therefrom and terminating, as shown in Fig. 3, in supporting arms 30 in the form of hooks, the purpose of which is to support the forward ends of the lateral scrapers when they are folded, as will be 10 hereinafter described.

At the rear of the machine and approximately in line with the rear wheels, is a crowning roller 31, which is disposed transversely of the machine so as to overlie the 15 central portion of the road when the machine is in position to operate. The roller 31 is made up of a number of sections 31^a, which are mounted on a shaft 32, as best shown in Fig. 7. These rollers are tapered 20 and are so proportioned and mounted on the shaft 32 that together they form a roller having a concave surface which conforms to the crown to be imposed upon the road. Obviously, by changing the sections of this 25 roller, the curvature of the roller as a whole may be varied, consequently varying the curvature of the crown of the road produced by the use thereof. The end portions of the roller shaft 32 are secured to a frame 33 pivotally connected, by forwardly-projecting draft-links 34 shown in Figs. 1 and 8, with the main frame 13, the pivots of said draft-links being shown at 35 in Fig. 1. By connecting the roller with the main 30 frame at a point forward of its own axis, the draft is properly applied thereto, and the draft-links 34 being pivoted the roller can rise and fall. When the machine is in use it is oftentimes desirable to apply as 35 much pressure as possible to the roller, and to this end, I provide means by which the entire weight of the rear portion of the machine may be thrown upon the roller supporting frame, and through it be applied 40 to the roller. The construction by which this is accomplished is best shown in Figs. 45 7 and 8. As therein shown, the rear axle 15 is provided with brackets 36 secured to the vertical portions thereof, preferably by 50 clamps 37. These brackets are provided with vertically-disposed sleeves 38 internally screw-threaded to receive the threaded portions of rods 39 having hand-wheels 40. The sleeves 38 overlie the side portions of 55 the roller frame 33 over the points where the ends of the roller shaft 32 are secured, so that by screwing down the rods 39, their lower ends may be forced down upon the side members of the roller frame 33, there- 60 by acting as lifting-jacks to raise the rear portion of the main frame and support it upon the roller supporting frame. By this means, great pressure may be applied to the roller, and its efficiency in crowning the 65 road be thereby greatly increased. In the

construction illustrated, the ends of the rods 39 do not bear directly upon the frame 33 but upon short angle-plates 41 which are fitted upon the frame 33 under the lower ends of the rod 39 and over the rear end 70 portions of the draft-bars 34, these parts being bolted, or otherwise suitably secured, together. The plates 41 may be easily removed and replaced when desired. For the purpose of steadyng the roller 31 and holding 75 it against endwise movement, the brackets 34 are provided with downwardly-projecting arms 42 opposite the ends of the roller shaft 32 and in position to bear against the vertical portions of the angle-80 plates 41, as shown in Fig. 7. Thus, when the roller frame moves vertically with reference to the machine frame, or the machine frame moves vertically with reference to the roller frame, the angle-plates 41 slide 85 against the inner surfaces of the arms 42, and the roller is steadied and held against endwise movement. When desired, the roller may be raised out of operative position, this being accomplished by means of 90 chains 43 which are secured to the rear portion of the roller supporting frame 33, as shown in Figs. 1 and 8, and are adapted to be wound upon drums 44 carried by a shaft 45 mounted transversely upon the rear portion 95 of the main frame 13, as shown in Fig. 3. This shaft is provided with a worm-wheel 46 shown in Fig. 3, which meshes with a worm 47, shown in Fig. 1, mounted on a vertical rod 48 having a hand-wheel 100 49. By rotating the hand-wheel 49 the shaft 45 may be rotated, thereby winding up the chains 43 upon their respective drums, or unwinding them, as the case may be, thereby raising or lowering the crowning 105 roller. Of course, when the roller is to be raised, the pressure rods 39 must be moved up sufficiently to permit the roller to be lifted. 50 indicates scrapers which bear upon the surfaces of the several roller sections, said scrapers being pivoted upon the roller frame 33, as shown at 51 in Fig. 8, and having arms 52 carrying weights 53 by which the scrapers are yieldingly pressed 110 against the surfaces of the roller sections. 115

In advance of the crowning roller, the machine is provided with means for preparing the road for the final rolling operation. This mechanism consists principally of two compound scrapers adapted to be projected 120 laterally at opposite sides of the machine at a variety of angles and provided with means for moving them to the desired position and firmly holding them there; also a scarifier centrally disposed so as to operate over the 125 crown of the road before the scraper devices operate thereupon. The arrangement of these parts is best shown in Fig. 4, in which 54-55 indicate the inner and outer members, respectively, of each of the two lateral 130

scrapers, and 56 indicates the scarifier. The inner members 54 of the lateral scrapers are preferably considerably shorter than the outer members 55 thereof, and the members 5 of each scraper are pivotally connected together, preferably in the manner shown in Fig. 5. Referring to said figure, it will be noted that in the construction shown the scraper 55 comprises an I-beam 55^a, to which 10 is pivotally secured a forked bracket 57 by a pivot-bolt 58, so that said bracket may rock about a horizontal axis. The bracket 57 embraces an I-beam 54^a which forms a part of the scraper member 54 and is pivotally connected therewith by a vertical pivot-bolt 59, as shown. Thus, the two members 54—55 of 15 each lateral scraper may swing in a horizontal plane to different angular positions with relation to each other, turning about the pivot 59, and at their juncture they may also be swung vertically to different angular positions with relation to each other, turning about the pivot-bolt 58. In other words, they are connected by a substantially universal 20 joint or coupling.

The rear end portions of the members 54 of the lateral scrapers are held in operative position and adjusted vertically by means of a hand-lever 60 mounted on the main frame 30 and provided with the usual segment 61 and latch 62 for locking it in different positions. The lever 60, as best shown in Fig. 12, is in the form of a bell-crank, its lower arm 60^a projecting forward and being connected by 35 a bar 63 with an arch 64, the ends of which are connected with the rear end portions of the scraper members 54, as best shown in Figs. 1 and 4. Thus, by operating the lever 60 the height of the rear ends of the scraper 40 members 54 may be adjusted as desired. The forward end portions of said scraper members 54 are held in position by bars 65, the outer or rear ends of which are connected to the scraper members 54 by bolts 66, as 45 best shown in Fig. 6. As therein shown, the bars 65, which are preferably double, are provided at their outer ends with stirrups 67 which rest upon ears 68 projecting from the I-beams 54^a, the bolts 66 passing through 50 the members of the bars 65, through the stirrups 67, the ears 68, and through corresponding ears 69 secured to the lower flange of the I-beams 54^a. The forward or inner end of each bar 65 is secured to a longitudinally- 55 extending draft-bar 70, which is also an I-beam, and is supported upon and secured to a cross-brace 70^a in the manner shown in Figs. 2 and 4. As shown in Fig. 2, two bars 71—72, which together form a double-ended 60 yoke, are secured upon the draft-bar 70 transversely of the machine, and the ends of the bars 65 are secured to said yoke by pins 73. The scraper members 54 may be vertically adjusted by means of rock-shafts 65 74 mounted at the sides of the main frame

and extending longitudinally thereof, as shown in Figs. 1 and 3. At their forward ends said rock-shafts are provided with crank-arms 75 connected by rods 76 with the forward end portions of the scraper members 54. The rear ends of the rock-shafts 74 are provided with worm-wheels 77 which are operated by worms 78 shown in Fig. 3, said worms being mounted on shafts 79 provided with hand-wheels 80. Thus, by rotating the hand-wheels 80, the operator may adjust the forward ends of the scraper members 54 vertically, as desired. The adjustment of the two scraper members 54 may be made simultaneously or separately so far as 80 the front ends thereof are concerned, but their rear ends being connected to the lever 60 are always moved together when said lever is operated.

It will be apparent that the rear or inner 85 end portions of the scraper members 55, being connected with the forward end portions of the scraper members 54, are also vertically adjusted by means of the hand-wheels 80. The outer portions of said lateral 90 scraper members 55 are vertically adjusted by means of chains, or other flexible connections, 81, which are operated by two cranes mounted on the main frame of the machine. As best shown in Figs. 3 and 9, 95 82 indicates an arch, the ends of which are secured to the side members of the machine frame 13 at a suitable intermediate point, and 83 indicates a cross-beam which extends across the main frame 13 opposite the lower ends of the arch 82. The arch 82 and beam 83 form the upper and lower bearings 100 for the masts 84 of two cranes, said masts being of I-beam or other suitable construction. They are provided with upper and 105 lower pivots 85—86, respectively, as best shown in Fig. 9. 87 indicates the booms of the cranes, which are secured to the masts 84 in any suitable way, their outer ends 110 being braced by rods 88, as shown in Fig. 1. 89 indicates guy-rods for the upper ends 115 of the masts 84. 90 indicates brackets secured to the masts 84 and carrying windlasses 91 having worm-wheels 92 operated by worms 93 carried by shafts 94 having hand-wheels 95, all as shown in Figs. 9 and 10. Thus, the drums or windlasses 91 swing with the masts 84 and booms 87. The chains 81 are adapted to be wound upon the drums 91, and consequently the chains always properly align with the drums on which they are wound. 96 indicates guide-rollers mounted at the outer ends of the booms 87, over which the chains 81 pass, and 97 indicates rollers secured intermediately to the 120 scraper members 55. As shown in Fig. 1, the outer ends of the chains 81 are secured to the boom before passing around the rollers 96—97. Obviously, by rotating the hand-wheel 95 at either side of the machine, the 125 130

corresponding scraper member 55 may be raised or lowered as desired, and the weight of each scraper may be sustained by its crane when the scrapers are swung in or 5 out, as hereinafter explained.

For the purpose of moving the outer ends of the scraper members 55 in or out, *i. e.*, toward or from the machine frame, I provide a system of levers in the form of a 10 toggle, with means for operating them from the machine platform. As best shown in Fig. 4, 98—99 indicate levers pivotally connected together at 100, the lever 98 being pivoted at 101 to a bracket 102 secured to the draft-bar 70, the outer end of the lever 99 being secured to the outer end portion of 15 the scraper 55 by a pivot 103 in substantially the same manner as that described in connection with the bar 65 and scraper member 54. 104 indicates a link, the outer end of which is connected with the pivot 100, its inner end being connected by a pivot 104^a with a sliding rack-bar 105 mounted in suitable guides 106 at the under side of the 20 machine frame, as shown in Fig. 1. The rack-bar 105 is in mesh with a pinion 107 (see Fig. 4) which is carried at the lower end of a vertical rod 108 provided with a hand-wheel 109 at its upper end, as shown 25 in Fig. 1. The arrangement of both sides of the machine is the same, and the parts are similarly numbered. Thus, by operating either hand-wheel 109, the levers 98—99 may be moved either to the position shown in 30 Fig. 4 so as to project the scraper members 55 laterally, or they may be swung back to the position shown in Fig. 3, thereby folding the scrapers in the manner shown in the latter figure. When folded, the forward 35 ends of the scraper members 55 are lifted into engagement with the hooks 30 so that the scrapers are then supported by said hooks and are held up out of the way so as not to interfere with the steering of 40 the machine. The toggle construction described is very powerful and holds the blades properly in position when in operation, besides making it practicable to shift them under load.

50 The scarifier 56, as shown in Fig. 4, is located centrally of the machine in advance of the inner scraper members 54. This scarifier has a V-shaped frame having a number of sharp teeth adapted to engage the surface of the road and break it up to a moderate depth so as to enable the scraping devices to level it off properly to permit of its being smoothed by the roller. This scarifier is provided with forwardly-projecting draft-bars 110 which at their forward ends are connected with vertically-slotted plates 111 shown in Figs. 1 and 4. By means of these slots, the plates 111 are connected to a draft-frame 112 by a pin 113 which passes 55 through said slots. The forward end of the

draft-frame 112 is connected by a pivot 114, shown in Figs. 1 and 4, to the draft-bar 28. Thus, the scarifier 56 receives the direct draft. The scarifier may be vertically adjusted and meanwhile maintained in a horizontal position by means of bell-crank levers 115—116 mounted on pivots 117—118, respectively, supported by the main frame 13, the upper arms of said levers being connected by connecting-bars 119 shown in 70 Fig. 1. The levers 115—116 are rocked by means of a screw-threaded rod 120, which extends longitudinally of the machine, its threaded end passing through a threaded opening in the upper arm of the lever 116, 80 as shown in Fig. 3, its rear end being fitted in a suitable bearing 121 and provided with a hand-wheel 122. The lever 115 is connected by connecting-rods 123 with the slotted plates 111, and the lever 116 is connected by connecting-rods 124 with the intermediate portion of the scarifier frame. Thus, by operating the hand-wheel 122, the levers 115—116 are rocked in unison, and consequently the scarifier may be raised and 85 lowered, its horizontal position being maintained during the operation. 125 indicates chains connected with the outer portions of the bars 65 and with the main frame 13 at a point in advance of the scraper members 90 54, as shown in Figs. 1 and 3, said chains serving to take the draft of said scraper members when in operation.

126 indicates a center scraper arranged centrally of the machine back of the inner 100 ends of the scraper members 54, as shown in Figs. 3 and 4, said scraper being supported by bars 127 pivotally connected at their forward ends with the outer portions of the scraper members 54, as shown at 105 128 in Fig. 1. The scraper 126 may be vertically adjusted by a lever 129 connected thereto by a rod 130, as shown in Fig. 1. The lever 129 is provided with the usual locking segment 131 so that the scraper 126 110 may be locked in its different positions of adjustment.

From the foregoing description, it will be apparent that the lateral scrapers may be projected at opposite sides of the machine 115 so as to extend forward at a greater or less angle with the machine frame, and that when so projected, by reason of the fact that each lateral scraper is composed of two jointed members, the lateral scrapers may be 120 adjusted to give the surface of the road the desired slope or crown. From time to time these scrapers may be adjusted while the machine is in operation, and when the machine is to be moved from place to place, 125 they may be folded under the frame and placed out of the way, to permit the machine to be driven through comparatively narrow gates or along narrow lanes. When the machine is in use, the scarifier cuts up 130

the crown of the road in advance of the scrapers and prepares it for the shaving and smoothing operations. By providing the horizontal lift for the scarifier and applying 5 the draft directly thereto, it cuts more evenly and operates more efficiently; besides, the main frame is relieved of the draft of the scarifier. Back of the lateral scrapers the central portion of the road is scraped and 10 smoothed by the auxiliary scraper 126, which, as has been described, may also be adjusted vertically to suit the varied conditions of the work. Finally, after the scraping operations, the road is rolled and 15 crowned by the crowning roller, which, as has been explained, may be pressed down with all the weight of the rear portion of the machine. Either end of the crowning roller may be adjusted separately so that its 20 action may be controlled to secure the best results. For transportation purposes, the roller may be raised out of contact with the ground, as has been described.

That which I claim as my invention, and 25 desire to secure by Letters Patent, is,—

1. A road machine comprising a main frame, scrapers arranged to project forward and laterally at each side of said main frame and to swing toward and from said 30 frame, toggle mechanism for each of said scrapers adapted to be actuated to move said scrapers laterally, rack bars mounted on said main frame and operatively connected with said toggle mechanism, and 35 means engaging said rack bars for moving the same to actuate said toggle mechanism.

2. A road machine comprising a main frame, scrapers arranged to project forward and laterally at each side of said main frame 40 and to swing toward and from said frame, inner and outer toggle members at each side of the machine pivotally connected together, the inner toggle members being connected with the main frame and the outer toggle 45 members with said scrapers respectively, links at opposite sides of the machine connected with said toggle members, rack bars mounted on the machine frame and connected with said links, and separate means 50 for operating said rack bars to adjust the position of said scrapers.

3. A road machine comprising a main frame, rear scraper members adapted to project forward and laterally at opposite sides

thereof, forward scraper members pivotally 55 connected with the outer end portions of said rear scraper members and projecting forward and laterally beyond said rear scraper members, means for laterally adjusting said forward scraper members, a 60 longitudinally extending draft bar, and means connecting said draft bar with the outer end portions of said rear scrapers.

4. A road machine comprising a main frame, front and rear wheels supporting 65 said frame, scrapers projecting forward and laterally at opposite sides of said frame, a roller carrying frame disposed centrally of the machine back of the inner end portions of said scrapers, forwardly projecting draft 70 links pivotally connecting said roller frame with said main frame, a shaft carried by said roller frame, a roller mounted on said shaft, and means at opposite sides of the machine frame for exerting downward pressure 75 upon the opposite side portions of said roller frame.

5. A road machine comprising a main frame, front and rear wheels supporting said frame, scrapers projecting forward and laterally at opposite sides of said frame, a roller carrying frame disposed centrally of the machine back of the inner end portions of said scrapers, a shaft carried by said 80 roller frame, a roller mounted on said shaft, and vertically movable screw-threaded rods 85 adjustably mounted at opposite sides of the rear portion of the main frame and adapted to bear upon the side portions of the roller frame for exerting downward pressure upon 90 said roller frame.

6. A road machine comprising a main frame, front and rear wheels supporting said frame, scrapers projecting forward and laterally at opposite sides of said frame, a 95 roller carrying frame disposed centrally of the machine back of the inner end portions of said scrapers, forwardly projecting draft links pivotally connecting said roller frame with said main frame, a shaft carried by said 100 roller frame, a roller mounted on said shaft, and vertically movable screw-threaded rods adjustably mounted at opposite sides of the rear portion of the main frame and adapted to bear upon the side portions of the roller 105 frame for exerting downward pressure upon said roller frame.

ORTUS E. MOATS.
